UNITED STATES PATENT OFFICE.

ADALBERT ZOLLINGER, OF LEIPZIG-EUTRITSCH, GERMANY, ASSIGNOR TO THE FIRM OF POPPER & COMPANY, OF LEIPZIG, GERMANY.

ENDLESS BOW FOR PIANO-VIOLINS.

No. 918,637.

Specification of Letters Patent. Patented April 20, 1909.

Application filed April 24, 1908. Serial No. 428,989.

To all whom it may concern:

Be it known that I, ADALBERT ZOLLINGER, a subject of the King of Saxony, residing at Leipzig - Eutritzs, in Germany, have 5 invented a certain new and useful Endless Bow for Piano-Violins, of which the following is a specification.

This invention relates to an endless bow for piano-violins.

10 Endless, traveling horse-hair bows for mechanically operated musical stringed instruments have been composed of parallel groups of hairs so arranged relatively to each other that the junctions of the hairs 15 are at different parts of the bow. By this means the formation of a rough transverse line is avoided, and the arrangement described is much superior to the arrangement of all the junctions side by side, but a highly 20 trained ear is nevertheless capable of detecting the presence of the junctions, more particularly if the bow is thin and the sound-board is highly convex, so that when the horse-hair is pressed against the string the 25 lower group of hairs yields and allows the string to slightly extend into the junction.

To obviate this disadvantage the invention comprises a loopholder or stretching member to be placed at the junction of the 30 hairs and arranged so that perfectly flat contact surfaces are produced. A junction of this kind, with a loop holder or stretching member is shown in the annexed drawing, in which—

Figure 1 is a perspective elevation and 35 Fig. 2 a side view of a junction with the horse-hairs passing around the loopholder or stretching member.

In the construction shown the horse-hairs ⁴⁰ *a* and *a'* are connected together at their adjacent ends and formed into loops at the points of junction *b*, and the loop holder or stretching members *d*, which is of wood or other suitable material, is inserted into said loops. The said holder or stretching member ⁴⁵ *d* covers the junction and compels the hairs at said junction to lie in one plane so that during the movement of the bow, *i. e.* during the playing of the instrument, the contact is as smooth and free from scraping as 50 when an ordinary bow is used.

What I claim as my invention and desire to secure by Letters Patent of the United States is:—

An endless bow for piano-violins, comprising a band consisting of a series of horse-hairs the adjacent ends of which are connected together and formed into loops at the points of junction and a loop holder or stretching member inserted in said loops, ⁵⁵ ⁶⁰ substantially as described.

In witness whereof I have signed this specification in the presence of two witnesses.

ADALBERT ZOLLINGER.
